UNITED STATES PATENT OFFICE.

CHRISTOPHER C. BRADLEY, OF SYRACUSE, NEW YORK.

THILL-COUPING.

No. 876,620.

Specification of Letters Patent.

Patented Jan. 14, 1908.

Application filed March 26, 1907. Serial No. 364,641.

To all whom it may concern:

Be it known that I, CHRISTOPHER C. BRADLEY, of Syracuse, in the county of Onondaga, in the State of New York, have invented new 5 and useful Improvements in Thill-Couplings, of which the following, taken in connection with the accompanying drawings, is a full, clear, and exact description.

This invention relates to certain improvements in thill couplings involving the use of a fixed jaw and a movable jaw hinged thereto and adapted to grasp between them a coupling pin. These jaws may be mounted either upon the clip or upon the thill iron, and the 15 essential object is to provide a simple, practical and durable quick-shift automatic take-up coupling capable of being manufactured at a minimum cost. In other words I have sought to make the take-up spring serve the 20 double purpose of a lever and locking means to hold the movable jaw in operative position without the use of the usual link by pivotally attaching one end of the spring to an extension on the movable jaw and returning the 25 other end of the spring upon itself to establish sliding connection with the thill iron or fixed jaw between the jaw pivot and pivotal connection of the spring with the movable jaw.

Other objects and uses will be brought out 30 in the following description.

In the drawings—Figure 1 is a sectional view of a thill coupling embodying the features of my invention. Fig. 2 is an inverted plan of the same, the movable jaw being 35 shown in its closed position in both views. Fig. 3 is a side elevation of the coupling jaws and operating means for opening and closing the movable jaw, the parts being shown in their open position.

40 In order to demonstrate the practicability of my invention, I have shown a coupling pin —1— as supported upon a suitable clip —2— on the front axle as —3—, said coupling pin being in this instance encircled by a yielding 45 sleeve —4— of rubber surrounded by a split metal shell —5—, the latter forming a metallic gripping face for the jaws. This coupling pin —1— and its inclosing sleeves —4— and —5— are adapted to be grasped 50 by a fixed jaw —6— and a movable jaw —7—, the fixed jaw being preferably integral with the thill iron as —8— while the movable jaw —7— is pivoted to the fixed jaw by a pin —9— in front of the coupling

pin —1— and is provided with a forwardly extending arm —10— having its front end pivotally connected by a pin —11— to one end of a U-shaped spring —12—. The other end of this spring —12— is provided with a curved bearing —13— movable 60 between the extension —10— of the movable jaw and thill iron —8— of the fixed jaw and having sliding connection with the latter between the pivotal pins —9— and 11—, that is the curved bearing —13— on the free end 65 of the spring —12— is slideable along and against the under side of the thill iron —8— to and from the pivotal pin —9— and, therefore, to and from a position at the rear of the pin —11— so as to cut the arc through 70 which the pin —11— swings.

It is evident from the foregoing description that by tensioning the free end of the spring so as to press by its own tension against the adjacent face of the thill iron or fixed jaw, 75 when moved to the rear of the arc of movement of the pin —11—, its tendency will be to press downwardly upon the arm or extension —10— thereby rocking the jaw —7— upon its pivot to its closed position and 80 affording a take up for the jaws upon the coupling pin.

When it is desired to open the jaw it is simply necessary to place the finger in the loop of the spring and draw downwardly 85 until the bearing —13— on the free end of the spring is drawn along the lower side of the thill iron —8— to a position in front of the arc of movement of the pin —11— whereupon the spring is released and may be 90 swung rearwardly under the movable jaw to allow the latter to be opened to its full limit.

What I claim is:

1. A thill coupling comprising a coupling pin and opposed jaws, one jaw being pivoted 95 to the other and extending some distance from the pivot at the opposite side of the jaw proper, and a spring pivotally attached at one end to the extension and having its other end adapted to swing across the arc of 100 movement of its pivot between the extension and thill iron of the fixed jaw in sliding contact with the latter.

2. A thill coupling comprising a fixed jaw and a movable jaw hinged thereto, and having a grip face at one side of its pivot and an arm at the opposite side of its pivot, the fixed jaw having an extension overlying the 105

arm, and a spring having one end attached to the arm and its other end in sliding engagement with the extension of the fixed jaw.

3. A thill coupling comprising a fixed jaw having an extension, a movable jaw provided with an arm projecting under the extension and pivoted to the fixed jaw, and a spring pivotally attached at one end to the arm and having its opposite end in sliding contact

with the extension of the fixed jaw and movable across the arc of movement of its pivotal connection with the arm.

In witness whereof I have hereunto set my hand this 20th day of March, 1907.

CHRISTOPHER C. BRADLEY.
